UNITED STATES PATENT OFFICE

ANDREW SIGFRID GUSTAFSON, OF CHATTANOOGA, TENNESSEE.

MINE-CAR.

No. 895,179.

Specification of Letters Patent.

Patented Aug. 4,

Application filed November 1, 1907. Serial No. 400,251.

To all whom it may concern:

Be it known that I, ANDREW SIGFRID GUSTAFSON, a citizen of the United States, residing at Chattanooga, in the county of 5 Hamilton and State of Tennessee, have invented a new and useful Mine-Car, of which the following is a specification.

This invention relates to the construction of cars and especially mine cars.

10 The principal object of the invention is to provide a truck of very simple but strong construction in which the truck will be perfectly rigid as regards endwise or lateral movement, while at the same time affording 15 vertical play of the wheel axles in order that the wheels may follow uneven or irregular rails, so that the wheels will at all times remain in contact with the rails and cannot climb to such position as to result in derailment.

20 A further object of the invention is to provide a perfectly rigid truck structure in which all of the frame is formed of channel or other structural iron rigidly secured together. 25 in such manner that the wooden parts may be readily added without disconnecting any parts of the frame and which will permit ready renewal of any of the wooden bottom, side or end members in case the latter become 30 broken.

35 A still further object of the invention is to provide an all metal frame in which the sills, binders, ties and axle pedestals are so connected as to mutually brace and reinforce each other and to insure the utmost strength and rigidity.

40 A still further object of the invention is to provide an all metal frame in which the longitudinal sills are bent at one end and extended in a vertical line to form braces for the closed end of the car.

45 A still further object of the invention is to provide a novel construction of pedestal adapted especially for connection to a channel bar or other form of structural iron bar, and further to so construct the pedestal as to prevent endwise play of the axles.

50 With these and other objects in view, as will more fully hereinafter appear, the invention consists in certain novel features of construction and arrangement of parts, hereinafter fully described, illustrated in the accompanying drawings, and particularly pointed out in the appended claims, it being 55 understood that various changes in the form,

proportions, size and minor details structure may be made without departing from the spirit or sacrificing any of the vantages of the invention.

In the accompanying drawings:—Fig. 1 is a perspective view of the metal frame of a mine car constructed in accordance with the invention. Fig. 2 is a transverse side view of the same on the plane of one of the axles. Fig. 3 is a perspective view of the bottom of the car. Fig. 4 is a bottom view of one of the pedestals detached. Fig. 5 is a view looking at the inner face of the pedestal. Fig. 6 is an end elevation of the pedestal.

Similar numerals of reference are employed to indicate corresponding parts throughout the several figures of the drawings.

In carrying out the invention, the frame is formed of structural iron, and while channel bars have been shown in the present invention, it is to be understood that angle iron, I-beams or other well known structural iron may be employed instead of the channel bars if desired.

The two side sills 10 are formed of channel bars, the side webs being turned inward and these bars are shown as extending inside the supporting wheels 11, although of course, they may be arranged outside the wheels in some instances. At one end the bars are turned upward to form end extensions 15 for the closed end of the car, it being understood that in cars of this class one end is permanently closed and the opposite end is provided with a hinged door of any desired type to permit discharge of the load at the tipple.

Extending transversely of the frame are a number of binders 16, three of which are shown in the present instance, and are formed, also, of channel bars. At the points where the ends of the binders are turned up around the outer edges of the sills, the edge webs of the latter are crimped or bent inward in order to insure a close fit, and the end portions of the binders are bent up in a vertical plane, then inward at an angle, and thence upward in another vertical plane in order to give the car of the usual shape, that is to say, a hopper like form in cross section. The edge webs of the channel bars are crimped or bent inward at the extreme upper ends, indicated at 18, where the cars are pivotally

with vertical swinging end gates, although this arrangement may be modified in any manner in accordance with the type of end gate to be used, and in the present instance is shown merely for the purpose of affording a convenient means for the attachment of the end gate carrying bridle 19 shown in Fig. 2.

In order to reinforce the end of the car, a cross brace 20 is employed, this brace being preferably formed of flat bar iron and being bolted or riveted at 21 to the upper ends of the extension portions 15 of the sills, while the flanges of said sill members are crimped or inbent at the fastening points. The opposite ends of the cross brace are bent around inward to follow the cross sectional contour of the upper portions of the end binder and are secured thereto by rivets 22. These form a very rigid support at the closed end of the car.

To the central portions of the bottom of the sills 10 are secured axle pedestals 23 of the construction best shown in Figs. 4 and 5. Each pedestal member is provided with a longitudinally disposed upper web 24 of a length somewhat greater than that of the pedestal proper, and of such shape in cross section as to fit snugly within the channel bar to which it is to be attached, and beyond this web, and slightly spaced therefrom is a vertically disposed flange 25 that fits against the outer face of the outer side web of the channel bar. This flange also serves the purpose of forming a wearing surface for the inside hubs of wheels, being made with a broad surface so as to take all lateral or horizontal thrust. This arrangement forms a very rigid support for the pedestal and at the same time reinforces the channel bar at the point where it is subjected to the greatest strain. That portion of the web 24 that projects beyond the end of the pedestal proper is of a thickness about equal that of the vertical webs of the channel bar and forms a seat for the reception of a cross tie 26 that is, also, formed of channel iron.

The opposite or lower side of each pedestal is recessed to form a pair of side flanges 28 spaced at a distance equal to the distance between the webs of one of the channel bars and arranged to receive a pedestal reinforcing bar 29, the ends of which fit down over the crimped ends of the bars 26 and also over the bottom of the longitudinally disposed upper web of the pedestal box 24 and up into and between the webs or flanges of the side sill 10, while the intermediate portions of said reinforcing bars are bent to follow the contour of the pedestals and are, also, bent at the center to pass under the center binder 16 while that portion of the reinforcing bar between the center binder and the pedestals is bent upward to fit within the side flanges of

the channel bar sill members 10, so that the structure is materially reinforced both lateral and longitudinal struts several members are united by bolts which pass through the reinforcing cross ties, pedestals and sills.

The inner ends of the pedestal are provided with projecting lips 30 that extend under and are afterwards bolted to the wooden bottom of the car. These are slightly spaced from each other to permit the passage of the axle, and at a point the inner wall of the pedestal is provided with a recess 32, the two recesses serving to receive collars 33 on the axles 34, and in this manner prevent longitudinal play of the axles.

One of the principal difficulties encountered in the operation of mine cars is the tendency of the wheels to ride up over especially where the latter are ungreased. To prevent this the wheels are usually with very high flanges, which are soon worn or chipped. In the present case this difficulty is overcome by making the openings 35 in the pedestals vertically elliptical in form, as shown in Fig. 5, so that the wheels will at all times remain in engagement with the track and are free to yield to conform to irregularities in the track, thus preventing any tendency of one or more of the wheels to ride up and derail the car.

The wooden bottom, side and end panels may be secured in place without removal of any of the frame fastenings, rivets, and any part of the wooden frame may be readily renewed when broken.

In cases when both ends of the car are permanently closed, the sills may be bent upward at both ends.

I claim:—

1. A combined truck and car frame comprising longitudinal sills bent upward at one end to support the end of the car, transversely extending binders rigidly secured to said sills and having upwardly extending end portions for the support of the car, the sills and binders being of structural iron and being permanently secured together independent of the binding and sides, axle receiving pedestals having web portions shaped to fit the channel bars and means for securing the pedestals to the sills.

2. A combined truck and car frame comprising longitudinal sills formed of structural iron and bent upward at the central end extensions, transverse tie bars secured to the sills and having upwardly extending end portions for the support of the sides of the car, transversely extending tie bars connecting the sills, axle receiving pedestals having webs fitting the faces of the sills and provided with upwardly extending portions forming seats for the pedestals.

and means for securing the pedestals to the sills.

3. A combined truck and car frame comprising longitudinal sills and binders rigidly secured to the sills, said sills and binders having upbent end portions to form supports for the vertical wall of the car, pedestals shaped to fit the lower faces of the sills, tie bars extending between the sills and engaging portions of the pedestals, and means for securing the tie bars and pedestals to the sill.

4. In a combined truck and car frame, longitudinal sills formed of flanged bars, transverse binders also formed of flanged bars and secured to the sills, all of the binders and sills having upturned end portions for the support of the vertical walls of the car, and end members securing the end portions of the end binder to the end portions of the sills, and pedestals secured to said sills.

5. In a combined truck and car frame, longitudinal sills formed of flanged bars, binders secured to the sills and, also, formed of flanged bars, pedestals each provided with a pair of spaced vertical webs extending from the end of the pedestals, transverse tie bars connecting the sills and secured to the projecting portions of the pedestals, and pedestal reinforcing strips bent to follow

the contour of the lower face of the sill, the center binder, and

6. In a truck of the class deformed of channel bars, pedestal their upper faces shaped to con lower faces of the channel bars, of the pedestals being provided forming a pair of spaced webs, reinforcing straps extending from bars and under the pedestal permanently secured to said channel bars.

7. In a truck of the class deformed of channel bars having turned webs, and pedestals having flanges fitting within said channel bars permanently secured thereto.

8. In a truck, a pedestal having receiving opening and providing inwardly extending flange, said recesses adjacent the inner pedestal, and a wheel supporting an annular flange fitting recesses.

In testimony that I claim the my own, I have hereto affixed in the presence of two witnesses

ANDREW SIGFRID
